US00D491079S

(12) United States Design Patent **(10) Patent No.:** **US D491,079 S**
Lim **(45) Date of Patent:** **** Jun. 8, 2004**

(54) ELECTRONIC THERMOMETER

(75) Inventor: **Young Jae Lim**, Seoul (KR)

(73) Assignee: **Samsung Corporation**, Kyungki-do (KR)

(**) Term: **14 Years**

(21) Appl. No.: **29/186,660**

(22) Filed: **Jul. 22, 2003**

(30) Foreign Application Priority Data

May 14, 2003 (KR) 30-2003-0013278

(51) LOC (7) Cl. **10-04**

(52) U.S. Cl. **D10/57**

(58) Field of Search D10/57, 52; 374/208, 374/163, 158, 169, 170, 183; 600/549

(57) CLAIM

The ornamental design for a "an electronic thermometer", as shown and described.

DESCRIPTION

FIG. 1 is a perspective view of an electronic thermometer according to the present invention.

FIG. 2 is a front view of the electric thermometer according to the present invention.

FIG. 3 is a rear view of the electronic thermometer according to the present invention.

FIG. 4 is a left side view of the electronic thermometer according to the present invention.

FIG. 5 is a right side view of the electronic thermometer according to the present invention.

FIG. 6 is a top plan view of the electronic thermometer according to the present invention.

FIG. 7 is a bottom plan view of an electronic thermometer according to the present invention.

FIG. 8 is a perspective view illustrating use of the electronic thermometer according to the present invention; and,

FIG. 9 is a front view illustrating use of the electronic thermometer according to the present invention.
